THROTTLE CONTROL LEVER

David Koonce, Bellaire, Ohio

Application May 25, 1938, Serial No. 210,078

2 Claims. (Cl. 74—530)

This invention appertains to new and useful improvements in throttle levers and more particularly to a lever which can be micrometrically adjusted without the use of dual quadrants and 5 detents.

Another important object of the invention is to provide a simplified throttle control lever the 10 detent of which offers means whereby vernier adjustment may be accomplished.

10 These and various other important objects and advantages of the invention will become apparent to the reader of the following specification.

In the drawings:

Figure 1 represents a side elevational view of 15 the lever.

Figure 2 is a sectional view taken substantially on the line 2—2 of Figure 1.

Figure 3 is a side elevational view of the controller.

20 Figure 4 is a sectional view showing the clutch means.

Figure 5 is a cross-sectional view on the line 5—5 of Figure 2.

Figure 6 is a fragmentary detailed sectional view on the line 6—6 of Figure 4.

Referring to the drawings wherein like numerals designate like parts, it can be seen in Figure 1, that numeral 5 represents the elongated lever which is pivotally connected as at 6 to the bracket 7.

30 Numeral 8 represents the quadrant having the gear teeth 9. Numeral 10 represents the throttle controlling rod which is pivotally connected to the lever 5 as at 11.

Numeral 12 represents a hollow gear structure 35 in which the pair of clutch shoes 13—13 is pivotally mounted as at 14. These shoes are of arcuate shape and each at its inner side is provided with an arcuate grooveway for receiving the semi-circular spring member 15 which tends to 40 expand the shoes against the inner side of the gear periphery.

The gear is mounted on the stub shaft 16, one 45 end of this shaft extending into the lever 5. One end of the shaft 16 is provided with the head 17 and the other end with the nut 18 and cotter key 19.

Extending through the lever 5 is the short 50 shaft 20. This shaft extending into the gear 12 and having the cam 21 mounted on its inner end and operative between the free ends of the shoes 13—13.

An arm 22 having the clamp end 23 is clamped to the outer end of the shaft 20. The other end 55 of the arm 22 is formed with a slot for receiving the lateral pin 24 on the slide bar 25 of the de-

tent means, this slide bar being divided into the sections a—b which are pivotally connected together as at c. A bell-crank shaped handle 26 is provided on the handle portion 27 of the lever 5 and to this is pivotally connected the section b 5 of the slide 25. The slide 25 is disposed through the guide 28 and bolts extending from the lever 5 and through slots 29 in the slide 25 are equipped with nuts to prevent displacement of the slide from the lever 5. A block 30 is suitably secured 10 to the quadrant 8 and over this rides the reduced extension 31 of the slide 25.

Thus it can be seen, that by drawing the handle 15 26 toward the handle 27, the cam 21 will be rotated in the gear so as to release the shoes 13 so that the spring 15 will contract the same and free the gear so that it can be ridden on the quadrant 8. Obviously, releasement of the handle 26 will result in the stopping of the gear and the securing of the same against further adjustment.

The guide 28 has an opening therethrough, 20 through which the rod 32 extending from the section a is slidable and interposed between this block 28 in the section a is the spring 33 which acts to return the cam 20 to a position expanding the shoes.

While the foregoing specification sets forth the invention in specific terms, it is to be understood that numerous changes in the shape, 25 size and materials may be resorted to without departing from the spirit and scope of the invention as claimed hereinafter.

Having described the invention, what is claimed as new is:

1. A control lever comprising a pivotal hand 35 bar, a quadrant, a gear carried by the hand bar and meshing with the quadrant, and holding means on the gear, said holding means comprising a detent carried by the hand bar and expanding means in the gear for holding the gear against rotation and in response to the detent means.

2. A control lever comprising a pivotal hand 45 bar, a quadrant, a gear carried by the hand bar and meshing with the quadrant, and holding means on the gear, said holding means comprising a detent carried by the hand bar and expanding means in the gear for holding the gear against rotation and in response to the detent 50 means, and spring means associated with the detent means for holding the expanding means expanded while the detent means is in normal position.

DAVID KOONCE.
